UNITED STATES PATENT OFFICE.

LEOPOLD KAUFMANN AND MAX HERZ, OF NEW YORK, N. Y.

DESIGN FOR CIGAR-BOXES.

Specification forming part of Design No. **11,270**, dated July 1, 1879; application filed May 15, 1879.
[Term of patent 3½ years.]

To all whom it may concern:

Be it known that we, LEOPOLD KAUFMANN and MAX HERZ, of the city of New York, in the county and State of New York, have invented a new and original Design for a Cigar-Box, of which the following is a specification.

Figure 1 is a perspective view of a cigar-box embodying our design, showing the box closed. Fig. 2 is a perspective view of the same box, showing it opened.

Similar letters of reference indicate corresponding parts in all the figures.

This invention relates to a new shape of cigar-box, the same being composed of a closed bottom, four upright side pieces, and four triangular top pieces, of which two triangles have a longer base and shorter perpendicular than the other two, as hereinafter more fully described.

In the drawings, the letter A represents a rectangular box of the shape of an ordinary cigar-box. The same is composed of a rectangular closed bottom of four side pieces, *b c d e*, and of four triangular boards, *B C D E*,

hinged, respectively, to the front, the sides, and back of the box. The triangles *C D* have a shorter base and longer perpendicular than the triangles *B E*, and are in fact acute-angled isosceles triangles, whereas the triangles *B E* are obtuse-angled isosceles triangles. When folded together, as in Fig. 1, the four triangles will abut and constitute a complete cover. When the box is opened these triangular pieces are folded apart, as in Fig. 2, imparting to the box a peculiar and novel appearance.

We claim as our invention—

The design for a box, the same being composed of a rectangular bottom, four uprights, *b c d e*, and of four triangular pieces, *B C D* and *E*, of which two are acute-angled isosceles triangles, and the other two obtuse-angled isosceles triangles, substantially as shown.

LEOPOLD KAUFMANN.
MAX HERZ.
